(Cl. D90—20)

To all whom it may concern:

Be it known that we, Charles M. Chupa, Preston
J. S. Forrest and David S. Hackley, citizens of
the United States, residing at Detroit, in the
county of Wayne and State of Michigan, and re-
siding in Pleasant Ridge, in the county of Oak-
land and State of Michigan, and residing in De-
troit, in the county of Wayne and State of Michi-
gan, respectively, have invented a new, original,
and ornamental Design for a Tire, of which the
following is a specification, reference being had
to the accompanying drawing, forming part
thereof.

The drawing is a perspective view of a tire,
showing our new design.

We claim:

The ornamental design for a tire, as shown.
